UNITED STATES PATENT OFFICE.

OSCAR W. FAUSER, OF BELLEROSE, NEW YORK.

DESIGN FOR LINOLEUM OR SIMILAR HARD-SURFACED FLOOR COVERING.

Application filed September 10, 1927. Serial No. 23,363. Term of patent 7 years.

To all whom it may concern:

Be it known that I, OSCAR W. FAUSER, a citizen of The United States, residing at 44 Hudson Road, Bellerose, in the county of Nassau and State of New York, have invented a certain new, original, and ornamental Design for Linoleum or Similar Hard-Surfaced Floor Covering (Case #5), of which the following is a specification, reference being had to the accompanying drawing, forming a part hereof.

The figure is a plan view of a portion of linoleum or similar hard surfaced floor covering, showing my design, it being understood that the design in the representative illustration is repeated throughout the extent of the linoleum or similar hard surfaced floor covering.

I claim:

The ornamental design for linoleum or similar hard surfaced floor covering, substantially as shown and described.

In testimony whereof, I affix my signature.

OSCAR W. FAUSER.
